UNITED STATES PATENT OFFICE.

ROBERT GARDNER SEAMAN, OF SUMMERHILL, PENNSYLVANIA.

WATER ARCH.

1,412,713.

Specification of Letters Patent. Patented Apr. 11, 1922.

Application filed May 7, 1920. Serial No. 379,599.

To all whom it may concern:

Be it known that I, ROBERT G. SEAMAN, citizen of the United States, residing at Summerhill, in the county of Cambria and

5 State of Pennsylvania, have invented new and useful Improvements in Water Arches, of which the following is a specification.

This invention relates to a water arch for a steam boiler furnace, and the object is 10 to provide for a more effective distribution of the heat units, and especially of the heat generated near the forward portion of the fire box of a locomotive boiler.

Certain types of arches, for effecting a 15 similar purpose, are described and claimed in my Patent No. 1,346,769, dated July 13, 1920, and in my application Serial Number 202,547, filed November 17, 1917, and in the present application there will be described 20 and claimed a type of apparatus, or of arch, which includes an upper series of concentric tubular elements, and a lower series of concentric tubular elements, the inner tubes in each instance serving to conduct or convey 25 the heated gases from the forward portion of the fire box, upwardly and rearwardly to a point where they pass from the passages of the arch and mingle with the currents passing from the other end of the fire box 30 directly over the water arch, and thence through the tubes of the boiler. The tubes surrounding the tubes above referred to, are connected with the water jacket of the furnace, and the temperature of the water in 35 the outer tubes is of course materially increased as the result of the passage of the gases through the inner tubes. Moreover, a passageway for the heated gases is provided between the upper and the lower series 40 of concentric tubes, and the upper tubes are covered with a layer of refractory material, retaining a considerable quantity of heat and giving it off after the maximum has been reached, and the fire over a portion of 45 the grate surface has died down to a certain extent.

The invention contemplates the provision of a water arch which shall include a head with a water compartment within the walls 50 thereof, such compartment having connection with the water jacket of a furnace, a plurality of series of concentric tubes, mounted as above indicated and terminating within the head, and an element of particu- 55 lar construction connected with and form-

ing a part of the arch and the lower forward end thereof, permitting the heated gases to enter the inner tubes, and affording a water connection with the outer tubes.

In the accompanying drawings, 60

Figure 1 is a vertical longitudinal section through the furnace and through the water arch,

Figure 2 is a section on line 2—2 of Figure 1, 65

Figure 3 is a section on line 3—3 of Figure 1,

Figure 4 is a view in perspective of the elements connected with the lower ends of the tubes of the arch. 70

In carrying out my invention, I provide a furnace structure including an upper and outer wall 10, and an inner wall 12 providing a water compartment 14. The tube sheet is shown at 15, the fire tubes of the boiler being 75 designated 16, and the upper and lower tubes being of the relative size indicated.

The head 18 of the arch extends the full width of the fire box, and includes a water compartment 21 having connection with the 80 pipes 22 and 23 extending vertically and having communication with the water compartment above the fire box. This head also provides a compartment 25 through which the heated gases pass from the arch into the upper portion of the fire box. Openings in the double wall of the head opposite the fire door are closed by means of plugs such as 26.

The lower portion of the arch consists of a casting of the form shown in Figure 4 having communication with the water jacket of the fire box by means of elbows such as 29. This casting is designated 30 and provides a water chamber 31 having communication with the water tubes 32 of the arch. 95

These tubes are in two series, termed an upper and lower series, and the two series are spaced apart to provide an intervening passageway 34 through which the heated gases may pass from that portion of the fire box 100 adjacent the tubes of the boiler, in the direction shown by the arrows, and thence into chamber 25 of the head of the arch, emerging through passageway 25' and passing thence through the upper portion of the fire box 105 where they are further heated by passing over the upper surface of the arch, assuming that at a given time the fire over that surface of the grate near the lower end of the arch has died down slightly, and that the 110

upper surface of the arch still maintains a temperature approximating that to which it was previously heated.

The inner tubes 33 also permit of the passage of heated gases, the current emerging from these tubes taking the same course through the head and the upper portion of the fire box. The ends of the outer tubes are reduced, as shown, and enter apertures provided in the lower casting 30 and in the head. The lower ends of the inner tubes are connected with casting 30 in the manner shown, the upper ends however being secured by apertured plugs designated 33'. The water jacket of the head is in communication with the water compartment in the side walls of the furnace, by means of elbows shown at 40.

By employing this construction, especially effective results are realized, and the danger 20 of injury to the tubes of the boiler is reduced to a minimum.

As will be inferred from the foregoing, an important feature of the arch is the covering for the upper series of tubes. This covering is shown at 42, and is of the material best suited to the purpose, the layer of material extending the full width of the arch, and therefore the full width of the fire box, as shown in Figures 2 and 3.

30 When a locomotive equipped with a super-heating apparatus is under steam and running under load, the dampers of the super-heater are open and the hot gases flow over the surface of the fire brick covering of the 35 water arch and into all of the tubes of the boiler, at the same time heating the fire brick to a high degree. When the engine is not under steam, the throttle valve being closed, the upper or larger super-heater tubes 40 are closed automatically by the damper of the superheater, and the gases then flow downwardly over the fire brick into the lower and smaller tubes, which remain open. The heated fire brick now radiate a portion 45 of the heat absorbed, and also deflect the heat of the flowing gases, directly against the tubes, preventing a sudden change of temperature, which tends to cause contraction of the flue sheet and to produce leaks 50 between that sheet and the ends of the tubes. These difficulties are reduced to a minimum, or eliminated, in the present construction.

What I claim is—

1. The combination with a furnace structure including exterior walls providing a 55 water jacket, of a water arch, and means for effecting communication between the water jacket and arch, said arch directing gases rearwardly through the firebox and thence forwardly over the arch to a tubular boiler, said arch comprising a lower transverse element, an upper transverse element 60 constituting a head, a series of tubes connecting the lower transverse element with the head and permitting the passage there-

through of heated gases, and tubes surrounding those first named, and having communication with the water jacket of the furnace, through said head.

2. The combination with a furnace structure the exterior walls of which provide a water jacket, of a water arch inclined upwardly from the lower forward portion of the firebox of the furnace to a point beyond the middle portion of the fire box, said arch 75 directing gases rearwardly through the firebox and thence forwardly over the arch to a tubular boiler, said arch including a head extending transversely and providing therein a water compartment and a chamber for 80 heated gases, the water compartment having communication with the water jacket of the furnace, and parallel and concentrically arranged ducts for conducting water and heated gases, respectively, from the lower forward portion of the arch to the interior of the aforesaid head.

3. The combination with a furnace structure including a firebox and including water legs formed in the side walls of the furnace, 90 of a water arch having communication with the water legs, said arch directing gases rearwardly through the firebox and thence forwardly over the arch to a tubular boiler, and comprising an upper and a lower series 95 of concentric tubes, the inner tubes of each series having their lower ends opening at the lower forward portion of the firebox, a head for the arch, the upper ends of said tubes opening into the head, permitting 100 gases to pass from the tubes through the head into the firebox above the arch, and the remaining tubes having communication with the water legs through the interior of the head.

4. The combination with a furnace structure including water legs formed in the side walls thereof, of a water arch positioned in the firebox of the furnace, extending transversely thereof between the side walls of the 110 firebox and inclined downwardly toward the lower tubes of the boiler, said arch including a plurality of concentrically arranged tubes forming an upper series, and similarly arranged tubes forming a lower 115 series, a passageway being provided between the two series, said arch also including a head and a lower transverse element, said lower element and head being in communication with the interior of the tubes, and permitting of the circulation of water and of 120 heated gases, the latter passing from the lower forward portion of the arch to the upper rear portion thereof, and the gases passing thence over the top of the arch, and a layer of heat absorbing material above the 125 upper series of tubes.

5. A water arch for a boiler furnace comprising a head formed with double walls providing a water space, a lower transverse ele- 130

ment formed with double walls providing a water space, a series of tubes in parallel relation and having communication with the water spaces, and tubes positioned within 5 those first named, extending beyond the ends thereof, through the water spaces, for conducting heated gases from the lower exterior end of the arch to the upper end of the arch, the walls of the head deflecting the 10 gases thence over the arch, and a covering of heat absorbing material for the tubes.

6. A water arch for a boiler furnace comprising a head formed with double walls providing a water space, said head also pro-

viding an inner chamber, a lower transverse 15 element having a water space therein, a series of tubes each having communication with the water spaces, tubes within those first named and extending through the water spaces, the lower ends of the tubes opening 20 exteriorly of the arch, and the upper ends opening into the inner chamber of the head, additional tubes spaced from those aforesaid and providing a passageway therebetween opening into the head, and a covering of 25 heat absorbing material for the arch.

In testimony whereof I affix my signature,
ROBERT GARDNER SEAMAN.
